[57] CLAIM

The ornamental design for a paint can attachment, substantially as shown and described.

DESCRIPTION

FIG. 1 is a top perspective view of a paint can attachment, showing my new design;

FIG. 2 is a top plan view thereof;

FIG. 3 is a bottom plan view thereof;

FIG. 4 is a side elevation view thereof; and

FIG. 5 is a front elevation view thereof.

The undisclosed side and rear portions of the paint can attachment are mirror images of the portions shown in FIGS. 4 and 5.
